UNITED STATES PATENT OFFICE.

LOUIS KOZELEK, OF SCHENECTADY, NEW YORK.

DESIGN FOR A VIOLIN.

Application filed July 5, 1922. Serial No. 2,967. Term of patent 14 years.

To all whom it may concern:

Be it known that I, LOUIS KOZELEK, a citizen of the United States of America, residing at Schenectady, in the county of Schenectady and State of New York, have invented a new, original, and ornamental Design for Violin, of which the following is a specification, reference being had to the accompanying drawing, forming part thereof.

The figure is a view in perspective of a violin, showing my new design.

I claim:

The ornamental design for a violin, as shown.

LOUIS KOZELEK.
